(57) **CLAIM**

The ornamental design for a guitar, as shown and described.

DESCRIPTION

FIG. 1 is a front perspective view of a guitar showing our design.

FIG. 2 is a rear perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is an enlarged view of a portion of the guitar taken at line-9 in FIG. 1.

FIG. 10 is an enlarged view of a portion of the guitar taken at line-10 in FIG. 1.

FIG. 11 is an enlarged view of a portion of the guitar taken at line-11 in FIG. 1.

FIG. 12 is an enlarged view of a portion of the guitar taken at line-12 in FIG. 1.

FIG. 13 is an enlarged view of a portion of the guitar taken at line-13 in FIG. 2.

FIG. 14 is an enlarged view of a portion of the guitar taken at line-14 in FIG. 2.

FIG. 15 is an enlarged view of a portion of the guitar taken at line-15 in FIG. 7.

FIG. 16 is a front perspective view of a guitar showing the second embodiment of our new design.

FIG. 17 is a rear perspective view thereof.

FIG. 18 is a front elevation view thereof.

FIG. 19 is a rear elevation view thereof.

FIG. 20 is a left side elevation view thereof.

FIG. 21 is a right side elevation view thereof.

FIG. 22 is a top plan view thereof.

FIG. 23 is a bottom plan view thereof; and,

(Continued)

FIG. 24 is an enlarged view of a portion of the guitar taken at line-24 in FIG. 17.

The evenly spaced broken lines immediately adjacent the shaded areas represent the bounds of the claimed design. All other evenly spaced broken lines represent the portions of the guitar that form no part of the claimed design. The dot-dash broken lines identify the enlarged views and form no part of the claimed design.

1 Claim, 24 Drawing Sheets
